UNITED STATES PATENT OFFICE.

PAUL A. HABERL, OF DENVER, COLORADO.

ARTIFICIAL FOOT.

SPECIFICATION forming part of Letters Patent No. 577,133, dated February 16, 1897.

Application filed May 11, 1896. Serial No. 591,060. (No model.)

To all whom it may concern:

Be it known that I, PAUL A. HABERL, a citizen of the United States of America, residing at Denver, in the county of Arapahoe and State of Colorado, have invented a certain new and useful Improved Artificial Foot; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to an improved artificial foot, and my object is to provide a device of this class which shall be simple in construction, economical in cost, reliable, durable, and efficient in use.

20 To these ends the invention consists of the features hereinafter described and claimed, all of which will be fully understood by reference to the accompanying drawings, in which is illustrated an embodiment thereof.

25 In the drawings, Figure 1 is a vertical longitudinal section taken through my improved artificial foot. Fig. 2 is an underneath view of the foot, the hinged movable parts being exposed. Fig. 3 is a section taken on the line $\alpha\alpha$, Fig. 2.

Similar reference-characters indicating corresponding parts in these views, let the numeral 5 designate the framework or body of the foot, preferably composed of some suitable wood. This frame is provided with a central depending projection 5^a and is transversely bored to receive the cylindrical extremity 6^a of the movable heel-piece 6. This cylindrical recess is provided with a rearward opening through which the heel-piece projects, the latter being formed sufficiently narrow at this opening to allow the necessary movement of the heel-piece when the foot is in use.

35 The central part 5^a of the frame is provided with a central longitudinal mortise 7, communicating with the transverse cylindrical recess and adapted to receive a tenon 8^a, formed on the rear extremity of the toe-piece.

40 8. The part 6^a of the heel-piece is centrally recessed to receive the rear extremity of the tenon 8^a. The part 6^a is provided with a central aperture registering with an aperture in the rear extremity of the tenon 8^a.

45 55 The heel and toe pieces are connected by

a hinge-pin 9 passing through the said registering apertures.

Between the heel and toe pieces and the body part 5 are placed layers 11 and 10, respectively, of sponge-rubber or some other suitable yielding or elastic material. Below the heel and toe pieces and also on each side of the latter is placed sponge-rubber 12 or other suitable, similar, or desirable material. The sponge-rubber may be secured in place 65 in any suitable manner, as by gluing it to the adjacent parts.

A rubber sheath (not shown) should be drawn tightly over the entire foot. Hence there is little or no liability for the sponge- 70 rubber to become disarranged or displaced.

The parts 6 and 8 being hinged together and reinforced by the elastic material, allow the artificial foot, as nearly as may be, all the movements of a natural member, thus afford- 75 ing the wearer the greatest possible comfort.

The foot may be fastened to the stump in any suitable manner. It may also be fastened to any construction of artificial limb.

Having thus described my invention, what I claim is—

1. An artificial foot comprising the body part and the independent heel and toe pieces movably attached to the body part and reinforced by some yielding substance placed between the said pieces and the body part substantially as described.

2. An artificial foot comprising the body part and the independent heel and toe parts movably attached to the body part, and reinforced by independent yielding substances placed both above and below the said movable part substantially as described.

3. In an artificial foot the combination of the body part and the independent heel and toe pieces movably hinged to the body part at a common point substantially as described.

4. In an artificial foot the combination of the body part having a depending central part 5^a, and the parts 6 and 8 hinged to the body part in such a manner as to be capable of movement independently of each other and projecting respectively to the front and rear of the part 5^a.

In testimony whereof I affix my signature 105 in the presence of two witnesses.

PAUL A. HABERL.

Witnesses:

ALFRED J. O'BRIEN,
G. J. ROLLANDET.
